(57) **CLAIM**

We claim the ornamental design for a light fixture, as shown and described.

DESCRIPTION

FIG. 1 is a perspective view of a light fixture showing our new design.

FIG. 2 is a first side view of the light fixture shown in FIG. 1.

FIG. 3 is a second side view of the light fixture shown in FIG. 1.

FIG. 4 is a first end view of the light fixture shown in FIG. 1.

FIG. 5 is a second end view of the light fixture shown in FIG. 1.

FIG. 6 is a top view of the light fixture shown in FIG. 1.

FIG. 7 is a bottom view of the light fixture shown in FIG. 1; and,

FIG. 8 is a cross-section view of the light fixture shown in FIG. 1, taken along line 8-8 of FIG. 1.

The broken lines shown in the drawings illustrate portions of the light fixture that form no part of the claimed design.

1 Claim, 8 Drawing Sheets
